UNITED STATES PATENT OFFICE.

MILTON S. TRACY, OF ROCKY HILL, CONNECTICUT, ASSIGNOR TO FREDERICK W. DROSTEN, OF ST. LOUIS, MISSOURI.

ROLL-PAPER HOLDER AND CUTTER.

SPECIFICATION forming part of Letters Patent No. 451,685, dated May 5, 1891.

Application filed May 23, 1890. Serial No. 352,830. (No model.)

To all whom it may concern:

Be it known that I, MILTON S. TRACY, of Rocky Hill, in the county of Hartford and State of Connecticut, have invented certain new and useful Improvements in Paper-Cutters, of which the following is a specification.

This invention relates to paper-cutters in which a roll of paper is held on a roller or mandrel the ends of which are journaled in bearings in a supporting-frame, and in which a gravitating knife is employed which is guided by inclined slots formed in the supporting-frame, the arrangement being such that the edge of the knife rests upon the periphery of the roll of paper and accommodates itself automatically to the decreasing size of the roll as the latter becomes reduced, the knife being adapted to sever the paper when the free end of the latter is pulled diagonally against the edge of the knife. An example of a cutter of this class, above referred to, is shown in Letters Patent granted to F. W. Drostén June 21, 1887, No. 365,334.

The present invention has for its object to provide certain improvements in cutters of this class, whereby the automatic conformation of the knife to the periphery of the roll may be made more perfect and the binding of the knife in its guiding-slots prevented.

To these ends the invention consists in the improvements which I will now proceed to describe and claim.

In the accompanying drawings, forming a part of this specification, Figure 1 represents an end elevation of a paper-cutter embodying my invention. Fig. 2 represents a rear elevation of the same. Fig. 3 represents a perspective view of a portion of my gravitating knife. Figs. 4 and 5 represent a modification.

The same letters of reference indicate the same parts in all the figures.

In the drawings, *a a* represent the end pieces of the supporting-frame, said pieces being rigidly connected by any suitable means—as, for example, by base *b* and a top piece *c*, to which said end pieces *a a* are screwed.

d represents the roller or mandrel on which the web of paper is wound in the form of the roll *e*. Said roller is provided with trunnions

or gudgeons *d'*, which are journaled in bearings formed by the ends of the inclined slots *f*, formed in the end pieces *a*, said slots being open at their outer ends to permit the introduction and removal of the gudgeons. 55

g represents the paper-cutting knife, which is provided at its ends with ears or lugs *g'*, which are oblique or diagonal to the body of the blade, and are formed to slide in inclined slots *h*, formed in the end pieces *a*. When the ears or lugs *g'* are in place in said slots, the under side of the blade rests upon the periphery of the paper roll *e*, the blade being adapted to rise and fall by means of the said 65 lugs and slots, so that when a new roll is put into the frame the blade may be raised so as to bear on the enlarged periphery of said roll, and as the roll becomes reduced by the removal of the paper the blade will fall automatically and remain in contact with the periphery of the roll until all the paper has been removed. It is important that the cutting-edge of the blade be in close contact with the periphery of the roll, so that the paper 70 may be severed satisfactorily by pulling outwardly and upwardly on the free end of the web.

It often happens that the periphery of the paper roll is eccentric to its axis of rotation, 80 so that as the roll rotates the knife is at times required to move upwardly in conforming to the eccentricity of the roll. It will be seen that the bearing of the knife against the roll only at or near the cutting-edge or outer end 85 of the knife causes the upward pressure exerted against the knife by the roll to tip the knife crosswise, and thus cause the ears or lugs at the ends of the knife to bind on the edges of the guiding-slots *h*, the portion of 90 the knife between the cutting-edge and the back acting as a lever. This difficulty has in many cases been so great as to prevent the rotation of the roll when the eccentricity of the latter is somewhat marked. To obviate 95 this difficulty, I provide lugs or projections *i* on the under surface of the knife at the back or rear edge thereof, said projections being formed to bear upon the periphery of the roll *e*, as shown in Fig. 1, so that the knife is 100 supported by the roll not only at its cutting-edge, but also at its back or inner edge. Said

projections are arranged substantially in line with the ears $g' g'$ at the ends of the blade. Hence the upward pressure of the roll when its periphery is eccentric is exerted on the 5 knife at both edges alike and in the direction of the movement of the ears $g' g'$ in their guiding-slots. There is, therefore, no possibility of the knife being tipped and the ears or lugs g' being caused to bind on the sides 10 of the slots h by such upward pressure.

To insure close contact between the cutting-edge of the blade and the periphery of the roll, I give the under side of the blade the bevel or inclination from the point 2, which 15 is back of the cutting-edge to the point 3, which is at the cutting-edge. The same result might be produced by giving the under side of the blade a slight concavity from its cutting-edge to its back or upper portion, the 20 object being to enable the under side of the blade to conform approximately to the periphery of the roll, so that the close contact of the cutting-edge with the periphery of the roll will be insured.

25 It is obvious that the knife may have but one lug i instead of two, and said lug may be at the central part of the knife or may extend along the greater portion of the length of the knife; or, if preferred, there may be more than 30 two lugs.

I do not limit myself to the employment of the ears g' and slots h as the means for guiding the knife, but may use the knife having the lug or lugs i in connection with means 35 for guiding the knife, such as are shown in Figs. 4 and 5, the knife being provided with groove or slot y in each end to receive guiding tongues or ribs formed on the supporting-frame. In any case, however, the means for 40 guiding the knife should be such as to permit only a substantially equal motion of both edges of the knife, and not a tipping motion or an upward swinging of the cutting-edge independently, so that when the paper is 45 pulled outwardly against the cutting-edge in the operation of cutting the paper, the entire weight of the knife and the friction due to the contact of the ears g' with the sides of the slots or to the contact of the sides of the 50 grooves shown in Figs. 4 and 5, with the said guiding tongues or ribs, will be utilized in supporting the cutting-edge against the strain or pull exerted on it by the paper.

I claim—

55 1. In a paper-cutter, the supporting-frame provided with means for supporting a roll of paper and with knife-guiding slots, combined with a knife having ears adapted to slide in

said slots, said knife being formed to bear on the roll not only at its forward or cutting 60 edge but also at its rear portion, whereby binding of the said ears on the sides of the slots during the upward movement of the knife by the roll of paper is prevented, as set forth.

65 2. In a paper-cutter, the supporting-frame provided with means for supporting a roll of paper, combined with a knife guided by said frame, and a lug or projection on its under side adapted to bear on the periphery of the 70 paper roll, as set forth.

75 3. In a paper-cutter, the combination, with the supporting-frame adapted to support a roll of paper and provided with knife-guiding slots, of a knife having ears adapted to slide in said slots and formed on its under side to approximately conform to the periphery of the paper roll, whereby its cutting-edge is kept in contact with said periphery, as set forth.

80 4. In a paper-cutter, the combination of the supporting-frame provided with means for supporting a roll of paper, and a knife guided on said frame by elongated projections or bearing-surfaces at the rear edge of the knife 85 and corresponding bearing-surfaces on the frame, whereby a tipping movement of the knife is prevented, said knife being provided with a lug or projection on its under side, arranged substantially in line with the portions 90 of the ends of the knife that are engaged with and slide on the frame and adapted to bear on the periphery of the paper roll, as set forth.

95 5. In a paper-cutter, the supporting-frame provided with means for supporting a roll of paper and with knife-guiding slots, combined with a knife formed to bear on the periphery of the roll both at its cutting-edge and at its back or rear edge and provided at its ends 100 with elongated ears arranged substantially in line with the rear edge-bearing portion of the knife, the contact of the rear edge of the knife with the paper preventing the binding of the said ears on the sides of the slots during upward movement of the knife by the roll of paper, as set forth.

105 In testimony whereof I have signed my name to this specification in the presence of two subscribing witnesses this 21st day of May, A. D. 1890.

MILTON S. TRACY.
